(57) CLAIM

The ornamental design for an electric grill, as shown and described herein.

DESCRIPTION

FIG. 1 is a front perspective view of the electric grill, showing our new design.

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view thereof.

The broken lines in the drawings depict portions of the electric grill that form no part of the claimed design.
